UNITED STATES PATENT OFFICE.

EDWARD E. HAMILTON, OF WESTFIELD, MASSACHUSETTS.

DESIGN FOR A BOW-HOLDER.

59,471.

Specification for Design.

Patented Oct. 25, 1921.

Application filed December 29, 1920. Serial No. 433,949. Term of patent 3½ years.

To all whom it may concern:

Be it known that I, EDWARD E. HAMILTON, a citizen of the United States, residing at Westfield, in the county of Hampden and State of Massachusetts, have invented a new, original, and ornamental Design for a Bow-Holder, of which the following is a specification.

Reference is to be had to the accompanying drawing, in which—

Figure 1 is a plan of a bow holder embodying my new design;

Fig. 2 is a side view thereof showing in dotted lines its manner of application to the hair, and

Fig. 3 is an end view.

I claim:

The ornamental design for a bow holder as shown.

In testimony whereof I have hereunto affixed my signature.

EDWARD E. HAMILTON.
